UNITED STATES PATENT OFFICE.

CHESTER B. WINN, OF BUFFALO, NEW YORK.

ARTIFICIAL LEG.

Application filed February 2, 1922. Serial No. 533,532.

To all whom it may concern:

Be it known that I, CHESTER B. WINN, a citizen of the United States residing at Buffalo, in the county of Erie and State of New York, have invented new and useful Improvements in Artificial Legs, of which the following is a specification.

This invention relates to artificial legs applicable to stumps amputated above the knee.

In such legs, it is necessary to provide a sufficient range of knee-action to allow for sitting and kneeling. As ordinarily constructed, such legs permit the shank or lower leg section to swing too far backward in walking, raising the foot too high from the ground and producing an awkward, unnatural gait. A leg of such ordinary construction has the further serious objection that in walking on an incline, especially down a hill or a flight of stairs, the leg is liable to bend backward at the knee-joint and suddenly buckle or collapse, causing the wearer to fall. Being conscious of this danger, the wearer acquires the habit of continually forcing the stump leg backward in an effort to overcome buckling when walking, producing a stiff, unnatural gait.

The object of my invention is the provision of a leg which while permitting the requisite knee-action for sitting and kneeling, is incapable of buckling under the conditions above mentioned, even when the wearer places his full weight upon it, thus rendering the leg absolutely safe and reliable and giving the wearer a sense of security which causes him to walk in an easy and natural manner.

In the accompanying drawings: Figure 1 is a sectional elevation of the invention, showing the leg in a standing position. Figure 2 is a similar view, but showing the leg in a walking position. Figure 3 is a fragmentary sectional view showing the position of the parts when the wearer is in a sitting posture. Figure 4 is a similar view showing the position of its parts when the wearer is in a kneeling posture. Figure 5 is a transverse vertical section on line 5—5, Fig. 1.

Similar characters of reference indicate corresponding parts throughout the several views.

10 represents the upper or thigh-section

of the artificial leg, 11 the shank or lower leg-section and 12 the foot-section. The thigh-section is pivotally connected to the shank-section in the usual manner; for example, by a pivot or knee-bolt 13 which is journaled in said thigh-section and rigidly connected to the customary straps or arms 14 secured to opposite sides of the shank-section, as shown in Fig. 5.

Secured at its lower end to the shank-section to move therewith, and extending upwardly through a slot 15 in the lower portion of the thigh-section, is a stop device, preferably in the form of a post 16, which serves not only to limit the forward movement of the shank-section to stop it at the proper point in its anterior action, as shown in Fig. 1, but also to arrest its rearward movement at the limit of its posterior action, as in the act of kneeling, this position being shown in Fig. 4. The lower end of this post is attached to the upper front side of the shank-section 12 by a bolt 17 or other appropriate fastening, while its upper end is hinged upon the knee-bolt and terminates above the latter in a lug or extension 18. It will be observed that by disposing this post at the front side of the shank-section, the central portion of the latter is unobstructed, permitting it to be hollowed out for lightness. The front end of the slot in the thigh-section terminates below the plane of the knee-bolt and forms an abutment 19 against which the front face of the stop post 16 is adapted to strike for limiting the anterior motion of the shank-section, as shown in Fig. 1. The other end of said slot terminates above the plane of the knee-bolt and forms a similar abutment 20 against which the rear face of the post is adapted to strike for limiting the posterior motion of the shank-section, as shown in Fig. 4.

Safety means are also provided for positively stopping the shank-section at a desired intermediate point in its posterior movement, that is, a point short of the rearward limit of its stroke, in order to prevent collapse or buckling of the leg and afford the wearer absolute safety in walking on uneven and hilly ground, or up and down stairs, or in boarding or leaving a street car or the like. This safety-stop normally occupies a position in which it arrests the shank-section at such intermediate point in

its posterior movement, but at the same time it is capable of being released or moved to an inoperative position at the will of the wearer, to allow the shank-section to swing 5 to the usual limit of its posterior movement when the wearer desires to sit, kneel or stoop. In its preferred form, this safety device is in the form of a vertically swinging gravity dog or pawl 21 located in the thigh- 10 section 10 and fulcrumed on a transverse pivot pin 22 secured to the lower front side of said section above the plane of the knee-bolt 13. The free end of this dog normally rests on a shoulder or semi-circular portion 15 23 of the stop post 16 which shoulder prevents it from dropping below that position. The dog stands normally in the path of movement of the exterior extension 18 of the stop post and when the lower shank- 20 section is swung backwardly, as in walking on level or hilly ground or going up or down stairs, the front face of said extension strikes the opposing rear face of the dog, thereby positively checking further posterior 25 movement of said shank-section, as shown in Fig. 2, and enabling the wearer to walk naturally with safety, ease and confidence.

The tail 24 of this dog extends into an opening 25 in the front side of the thigh- 30 section where it is accessible to the wearer through his clothing, enabling him to conveniently move the dog to its retracted or inoperative position, shown by dotted lines in Fig. 1, when he wishes to assume a sitting, stooping or kneeling position, as shown in Figs. 3 and 4. Upon depressing the tail to such dotted line position for this purpose, the dog proper is swung upwardly clear of the post-extension 18, permitting the shank- 35 40 section 11, to swing to the extreme limit of its posterior position, if desired. When the wearer again stands erect, the gravity dog rides over said post-extension and automatically drops to the normal position shown in Fig. 1, ready to again restrict the posterior movement of the shank section to the safety range for walking.

It will thus be noted that the post 16 and the co-operating ends of the thigh-section 50 slot constitute main stops for limiting the shank-section at the extremities of its anterior and posterior movements, while the retractile dog 21 in conjunction with said post constitutes an auxiliary safety stop located between those main stops for arresting the shank-section at a point short of its extreme posterior movement.

The front and rear faces of the stop post 16 and its extension 18 are preferably provided with an elastic bumper or cushion 26 of rubber, felt or similar material, and the dog 21 is provided with a similar bumper 27. The provision of these bumpers insures a quiet and smooth action of the lower 65 shank-section both in its anterior and post-

erior movements. In addition to this function with the stop-extension 18 strikes the dog 21, as in walking, these resilient bumpers assist in propelling the shank-section 11 forward, producing a graceful, natural step. 70

In walking up or down stairs or a hill, the thigh-section 10 swings backward to the intermediate or saftey stop position, enabling the wearer to place his entire weight on the artificial leg, when in that desired position, 75 and making walking safe and certain. Especially is this the case in boarding or leaving a street car or railroad train. In such cases, the arrest of the shank-section at such intermediate point materially decreases the 80 length of the artificial leg from the foot to the socket of the thigh-section, aiding the wearer in ascending or descending hills or stairs, while maintaining his entire weight on the artificial leg. 85

While I have herein shown and described one embodiment of my invention which has proved satisfactory in practice, I do not wish to be limited to the particular construction, as the same may obviously be modified in various respects within the scope of the appended claims, without departing from the spirit of the invention. 90

I claim as my invention:

1. The combination of a thigh-section, a shank-section, pivotally connected to said thigh-section, main stop means for limiting the shank-section at the extremities of its anterior and posterior movements, and an auxiliary safety-stop under control of the 100 wearer for arresting the shank-section at a point short of its extreme posterior movement. 95

2. The combination of a thigh-section, a shank-section pivotally connected to said thigh-section, a part carried by one of said sections for limiting the anterior and posterior movements of said shank-section, and a releasable part carried by the other section and co-operating with said first-named 110 part for stopping the shank-section at an intermediate point in its posterior movement. 105

3. The combination of a thigh-section having a slot in its lower end, a shank-section connected to said thigh-section by a pivot, a stop-member hinged upon said pivot and extending through said slot, the lower end of said member being attached to said shank-section to move therewith and the ends of said slot forming abutments for said stop member to limit the anterior and posterior movements of the shank-section, and means on said thigh-section co-operating with said stop member for normally checking the movement of said shank-section beyond a 120 predetermined point in its posterior action. 115

4. The combination of a thigh-section having an opening, a shank-section pivotally connected to said thigh-section, a stop-member attached to the shank-section to move 130

therewith, and a retractable stop-device mounted on the thigh-section and co-operating with said hinged member for normally stopping said shank-section at an intermediate point in its posterior movement, said stop device having a releasing member extending into the opening of the thigh-section.

5. The combination of a thigh-section having a slot in its lower end, a shank-section connected to said thigh-section by a pivot, a stop-post hinged upon the pivot of said section and attached at its lower end to the shank-section to move therewith, said post 10 extending through said slot and being provided above said pivot with an extension, and a retractile stop-dog fulcrumed in said thigh-section and normally disposed in the path of movement of said extension to stop 15 the shank-section at a desired intermediate point in its posterior movement, said thigh-section being provided adjacent said dog 20 with an opening through which the same is

accessible for disengaging it from said post-extension.

6. The combination of a thigh-section, a shank-section pivotally connected to said thigh-section, a part carried by and movable with one of said sections, and a part mounted on the other section and co-operating with 25 said first-named part for stopping said shank-section at an intermediate point in its posterior movement, said co-operating parts being provided with bumpers of elastic material.

7. The combination of a thigh-section, a shank-section pivotally connected to said thigh-section, a stop-member secured to the shank-section and extending into the thigh-section, and a releasable stop-dog mounted 30 on the thigh-section and normally disposed in the path of movement of said stop member, said stop member and said dog being provided with elastic bumpers.

CHESTER B. WINN.
